UNITED STATES PATENT OFFICE.

LOUIS YCRE, OF SAN FRANCISCO, CALIFORNIA.

BAKERY APPLIANCE.

1,240,000.

Specification of Letters Patent. Patented Sept. 11, 1917.

Application filed May 23, 1917. Serial No. 170,497.

To all whom it may concern:

Be it known that I, LOUIS YCRE, a citizen of the United States, and a resident of San Francisco, in the county of San Francisco 5 and State of California, have invented a new and useful Improvement in Bakery Appliances, of which the following is a specification.

My invention is an improvement in bakery appliances and the invention has for its object to provide an appliance especially adapted for the forming of French rolls, wherein a table is provided for supporting a board carrying the dough, and a plurality 15 of blades having guided movement toward and from the table and counterweighted to hold the blades elevated, the guides for the blades having means for permitting the blades to be moved laterally when in cutting 20 position to separate the rolls.

In the drawings:—

Figure 1 is a perspective view of the improved appliance,

Fig. 2 is a transverse vertical section, 25 Fig. 3 is a section on the line 3—3 of Fig. 2, looking in the direction of the arrows adjacent to the line,

Fig. 4 is a top plan view of the dough board.

The present embodiment of the invention 30 comprises a table 1 having its top recessed to form flanges 2 and 3 at its end and at one side, the other side being open, and the table is supported by the usual legs 4. Near 35 each side of the table and at the opposite end thereof pairs of standards 5 and 6 are arranged, the standards 5 being of greater height than the standards 6, and each standard is provided on its inner face with a vertical groove 7 and 8 respectively. Blade carrying bars 9 and 10 are mounted in the 40 respective standards, the ends of the bars 9 and 10 being offset upwardly as indicated at 45 11 and engaging the grooves of the standards. Each of the ends 11 of each bar has a notch or recess 12, and a roller 13 is journaled in each notch or recess, each roller engaging the bottom of the adjacent groove 7 or 8 as the case may be. Each bar 9 and 10 50 carries a blade 14 and it will be noticed that the lower end of each guide groove 7 and 8 is enlarged laterally at both ends as indicated at 15, to permit the blade supporting bars to be swung laterally to cause the blades 55 to separate the rolls after they have been cut.

Each blade and its supporting bar is counterweighted by a counterweight 16, the said counterweights being connected with cords 17 which pass over pulleys 18 and 19 60 to a connection with the adjacent end 11 of the adjacent blade supporting bar 9 or 10. The roller 18 is on the outer face of the standard and the roller 19 is on the top of the standard and the counterweights are supported at the outer faces of the standards. 65 These weights are just sufficient to lift the blades and the supports when they have been released after cutting the dough.

In Fig. 4 is shown a board or tray for 70 supporting the dough. The said board or tray comprises a base or bottom 20 having side and end walls 21 and 22 respectively, and having a partition wall 23 extending longitudinally of the center of the board and 75 engaging at its ends the end walls 22. From the inner face of each side wall and from each face of the partition wall spaced partitions 24 extend toward the center of the two compartments formed between each side 80 wall and the partition wall, the members of the four series of partitions being in alignment, and the members of the series in each compartment are spaced apart at their adjacent ends, as shown, to permit the passage 85 of the blades and their lateral movement.

In operation, the dough is laid in the double compartments formed by the partitions 24 and the tray is placed on the table between the flanges in the manner shown in 90 Fig. 2. Spacing members 25 are secured to the end walls 3 of the table, to properly space the tray beneath the blades 14 and when the tray is in place the blades are pulled down successively, cutting through 95 the dough after which they are moved laterally to separate the cut ends. After the rolls have been cut the tray is ready to go to the oven.

The improved tray is designed for fifty- 100 six rolls, but it will be obvious that it may be larger or smaller, dependent upon the size of the cutting machine. The rolls may be very easily removed from the tray, by placing a sheet of canvas over the tray. 105 This canvas sheet is cut through by the knives and it permits the rolls to be lifted from the tray with the greatest facility.

The device can also be made with only one standard with the knife or even both knives 110 attached to it, and this would change nothing of the working principle of the device.

I claim:—

1. A bakery appliance comprising a table having upstanding flanges at its rear and end walls, a pair of standards near each side of the table and at opposite ends thereof, one pair being of greater height than the other, each standard having on its inner face a vertical groove enlarged laterally at both sides at the bottom of the groove, a blade support having its ends engaging the grooves of each pair, and carrying a cutting blade, the enlargements at the bottom of the grooves permitting the support to be moved laterally, and counterweight mechanism for lifting the blade supports, each blade support engaging the bottom of the adjacent groove, said counterweighting mechanism comprising weights, flexible members connecting the weights to the blade supports, said weights being at the outer faces of the standards, and direction elements for the flexible members.
2. A bakery appliance comprising a table, having upstanding flanges at its rear and end walls, a pair of standards near each side of the table and at opposite ends thereof, one pair being of greater height than the other, each standard having on its inner face a vertical groove enlarged laterally at both sides at the bottom of the groove, a blade support having its ends engaging the grooves of each pair, and carrying a cutting blade, the enlargements at the bottom of the grooves permitting the support to be moved laterally, and counterweight mechanism for lifting the blade supports.
3. A bakery appliance comprising a table having upstanding flanges at its rear and end walls, a pair of standards near each side

of the table and at opposite ends thereof, one pair being of greater height than the other, each standard having on its inner face a vertical groove enlarged laterally at both sides at the bottom of the groove, a blade support having its ends engaging the grooves of each pair, and carrying a cutting blade, the enlargements at the bottom of the grooves permitting the support to be moved laterally and counterweight mechanism for lifting the blade supports, each blade support engaging the bottom of the adjacent groove.

4. A device of the character described comprising a table, a pair of standards near each side of the table, the members of the pairs being at opposite ends of the table, a blade support for each pair of standards, the ends of the support having guided movement in the standards, each support carrying a cutting blade, the guiding mechanism having means at their lower ends for permitting the support to be moved laterally in both directions.

5. A device of the character specified, comprising a table having upstanding flanges at its ends and one side, a pair of cutting blades having guided movement toward and from the table and a dough supporting tray fitting the table between the flanges and having double compartments for holding dough for two rolls, the walls of the compartments being cut away at the position of the blades.
